UNITED STATES PATENT OFFICE.

FRANZ GAEDE, OF FORT WURTTEMBERG, NEAR METZ, GERMANY.

DRIP-GUARD FOR BRUSHES.

1,398,894.

Specification of Letters Patent. Patented Nov. 29, 1921.

Application filed March 5, 1915. Serial No. 12,467.

(GRANTED UNDER THE PROVISIONS OF THE ACT OF MARCH 3, 1921, 41 STAT. L., 1313.)

To all whom it may concern:

Be it known that I, FRANZ GAEDE, residing at Fort Wurttemberg, near Metz, in the Imperial Province of Lorraine, Germany, 5 have invented certain new and useful Improvements in Drip-Guards for Brushes, of which the following is a specification.

This invention relates to drip-guards for use on shaving and other brushes, as well 10 known, and it has among its objects to produce a device of this class, which shall possess superior advantages in point of simplicity, durability and general efficiency.

More especially, the invention consists of 15 the construction and arrangement of the drip-guard in such manner, that the latter is to be used as a handle.

It also comprises details of construction 20 which will be more fully explained by reference to the accompanying drawing, which illustrates a preferred form of embodiment of the invention in longitudinal section.

In the drawing, *a* represents the true brush, which is fixed in any well known 25 manner to the shaft *b*, the end *c* of which is flattened. Further, the shaft *b* has a screw-threaded part *d* for the connection with the receptacle *e*. This receptacle is adapted to receive the dripping of the brush *a*, and its

bottom *f* has a threaded aperture corresponding to the part *d* of the shaft *b*. The outer form of the receptacle *e* is that of a suitable handle.

Inside of the wall of the receptacle are arranged deflectors *h*, consisting of inward-flaring flanges. It is advantageous, also to provide such a deflector *i* on the shaft *b*. These deflectors will prevent the gathered liquid to flow out when the receptacle is 35 tilted.

To protect the screw-connection against the entering of moisture, the shaft *b* possesses a flange-like enlargement *g*.

Having thus described my invention, I claim as new and desire to secure by Letters 40 Patent—

A drip-guard for use on shaving and other brushes, comprising in combination a receptacle in the form of a handle, having an opening in its top and deflectors inside 50 of the wall, and a deflector arranged on the shaft of the brush.

In testimony whereof I affix my signature in presence of two witnesses.

FRANZ GAEDE.
